UNITED STATES PATENT OFFICE

116,326

DESIGN FOR AN AIRPLANE

Peter S. L. West, Brooklyn, N. Y.

Application June 28, 1939, Serial No. 85,744

Term of patent 14 years

To all whom it may concern:

Be it known that I, Peter S. L. West, a citizen of the United States of America, residing at Brooklyn, in the county of Kings and State of New York, have invented a new, original, and ornamental Design for an Airplane, of which the following is a specification, reference being had to the accompanying drawing, forming a part thereof.

I claim:

The ornamental design for an airplane, as shown and described.

PETER S. L. WEST.
